COMBINED TESTING DOCK AND SALVAGE VESSEL

Application filed February 20, 1928. Serial No. 255,686.

This invention relates to ship construction, and more particularly to what I term a combined testing dock and salvage ship.

One of the main objects of my invention is to provide a ship construction of the character stated in which the ship hull is provided with a compartment for reception of a submarine boat to be tested, the hull being formed in sections, detachably secured together and having means for controlling the buoyancy of such sections, whereby the submarine boat may be readily floated into the testing dock or compartment. Another object is to provide means whereby a diver 13 working from the ship can enter the water well below the surface thereof so as not to be subjected to the action of rough seas at the surface. A further object is to provide simple and efficient means whereby the ship 20 is well adapted for raising heavy loads by its buoyant effect. A still further object is to provide efficient means for mooring the ship from a plurality of points along the sides thereof whereby the ship may be effectively 25 moored so as to maintain its position under unfavorable weather and current conditions. Further objects and advantages will appear from the detail description.

In the drawings:—

Fig. 1 is a sectional view taken substantially on line 1—1 of Fig. 2, the terminal stern portion of the ship being shown in elevation;

Fig. 2 is a plan view of the ship;

Fig. 3 is a section taken substantially on line 3—3 of Fig. 1;

Fig. 4 is an enlarged fragmentary detail section taken substantially on line 4—4 of Fig. 3;

Fig. 5 is a fragmentary sectional view 40 through the adjacent ends of the hull sections, parts being shown in elevation, illustrating the securing means therefor;

Fig. 6 is a section taken substantially on line 6—6 of Fig. 5;

Fig. 7 is a plan view showing the apparatus for effecting the lifting of heavy loads by the buoyancy of the ship's hull;

Fig. 8 is a bow view of the hull with the apparatus of Fig. 7 applied thereto;

Fig. 9 is a section taken substantially on line 9—9 of Fig. 1.

In constructing the ship in accordance with my invention the hull is formed in two sections, a main hull section 1, and a bow section 2. Section 1 is provided with an inner hull having an aft portion 3 of circular cross section and a forward portion 4 which is of increased height and includes a lower substantially circular section 5 and an upper section 6 shaped to accommodate the conning tower of a submarine boat. This inner hull forms an air and water tight chamber which opens through a bulkhead 7 at the forward end of section 1 and is of a strength to resist the high pressures to which it is necessarily subjected in testing submarine boats. The chamber or compartment thus formed is adapted to receive a submarine boat floated thereinto through the open end of the compartment. The other end of this compartment is closed by a bulkhead 8.

The space between the outer hull of the main section 1 and the inner hull which defines the submarine boat receiving compartment is divided by suitable partitions or bulkheads to form ballast tanks 9 at opposite sides of the inner hull or compartment, and a fuel storage tank or space 10 below the compartment. A bulkhead 11 extends transversely of the compartment or space beneath the inner hull and forms with the lower portion of bulkhead 7 a trimming tank 12. A second trimming tank 13 is provided at the stern of the main section 1. A deck 14 is provided in the plane of the top of the smaller portion 3 of the submarine boat receiving compartment, and a second deck 15 is provided in the plane of the top of the enlarged forward portion of this compartment. These decks are provided with suitable hatches 16 and 17 which give access to the boat receiving compartment and are suitably secured and constructed to withstand the high pressures in this compartment. Section 1 also includes a main deck 18. The decks 14 and 15 are sheltered and provide ample space for living quarters, store rooms, work rooms, shelter for warping and hoisting machinery, etc. The hull also includes the engine room or com- 95 100

partment 19 and, by providing suitably disposed bulkheads, various compartments necessary or desired, may be provided within the hull, as is well understood in the art.

- 5 Section 1 also includes a diving well or trunk 20 opening through the main deck 18 and through the bottom of the hull, this trunk having a telescoping section 21 having associated therewith any suitable means, not shown, for raising and lowering said section, permitting the diver to enter the water at an appreciable depth below the surface. The upper end of the diving well or trunk 20 opens into a water tight compartment 22 on the main deck, this compartment being provided with suitable hatches 23 giving access thereto from the main deck. This compartment is adapted to contain suitable apparatus for use in diving operations and for raising and lowering the extension member 21 of the trunk.

For the sake of clearness in illustration and description, the hull of the boat is illustrated semi-diagrammatically, the steering and propeller apparatus, and the internal mechanism of the boat being omitted as such mechanism and apparatus is well understood by those skilled in the art and forms no part of my invention, except in so far as it cooperates with the novel construction herein illustrated and described for effecting the desired results. In practice, the dock or compartment for receiving and testing a submarine boat has the necessary fittings for regulating the position of the submarine and for securing it in position. This compartment also has associated therewith the usual venting, blowing, flooding and pumping connections. It will also be understood that suitable means are provided for emptying and filling the ballast and trim tanks, supplying fuel to the engine, etc. All of this is well understood in the art and need not be illustrated nor described in detail.

45 The bow section 2 of the hull has its aft end closed by a water tight bulkhead 24 and is provided with a plurality of ballast and trim tanks 25, formed by appropriate bulkheads.

50 Bulkhead 7 of section 1 is provided on its forward face with a bead 26 which co-acts with a gasket 27 on bulkhead 24 (Fig. 4) for effecting a fluid tight closure of the forward end of the boat receiving compartment of section 1 when the two sections of the hull are secured in operative relation.

For securing sections 1 and 2 together I provide a plurality of cylinders 28 in which operate pistons 59. A piston rod 30 is secured to each piston 29 and operates through a suitable stuffing box 31 in the cylinder head. This piston rod 30 also operates through a stuffing box 32 in the bulkhead 7. At its forward end the rod 30 is provided with a head 33 of substantially rectangular shape,

the piston rod being of T-form. Head 33, when disposed at right angles to its position shown in Fig. 5, passes through a corresponding opening 34 in bulkhead 24 (Fig. 6). A suitable cover or cap 35 is secured to the inner face of bulkhead 24 and extends over and about the opening 34 so as to form a water tight closure about the same. An arm 36 is suitably connected to the piston rod 30 for turning the same and any suitable means may be connected to this arm for turning the rod 30 through an angle of 90 degrees in either direction. The hull section 1 is provided with a plurality of the piston or securing rods 30 disposed in a circle about the open end of the submarine boat receiving compartment, and bulkhead 24 of section 2 is provided with a plurality of similarly arranged openings 34.

For initially aligning the hull sections 1 and 2 and holding them against relative transverse movement, I provide two aligning members 37, which are suitably secured to the main deck 18^a of section 2. Each of these members is provided with a rearwardly extending reduced portion 38 adapted for insertion through a pair of eye members 39 and 40, secured in suitable manner to deck 18 of section 1. As will be noted more clearly from Fig. 4, the opening of member 39 is flared from its aft to its forward end to facilitate entry of portion or element 38 of member 37 thereinto. Each of the members 37 is provided, at the rearward end of elements 38 thereof with an opening forming an eye 41 for reception of a line or cable which may be passed about a power driven drum for pulling the members 37 into position through the eye members 39 and 40, moving the sections 1 and 2 of the hull into alignment adjacent each other.

After section 2 has been moved into position adjacent section 1 and in proper alignment therewith, in the manner described, the rods 30 are projected by admitting a suitable pressure fluid in rear of the pistons 29 in the cylinders 28. At this time the rods are turned

cylinders 28. At this time the rods are turned into such position that the heads 33 thereof will pass through the openings 34. The rods are then turned through an angle of 90 degrees to dispose the heads 33 at right angles to the openings 34 (Fig. 6), after which the pressure in back of the pistons 29 is released and pressure fluid is admitted in front of the pistons, thus forcing the section 2 tightly against section 1 of the hull and holding it in this position. Any suitable means well known in the art may be employed for controlling the admission and exhaust of pressure fluid to the cylinders, and it is not thought necessary to illustrate or describe such means in detail. When the two sections of the hull are thus secured together the members 37, which possess comparatively great mechanical strength, are of very material assistance 120 123 130

in securing the section 2 in proper position and in resisting the stresses to which this section is necessarily subjected.

In using the ship for testing submarine boats the sections 1 and 2 of the hull are released from each other and separated exposing the open forward end of the submarine boat receiving compartment. The buoyancy of section 1 is then reduced by means of the ballast tanks, this section being maintained on an even keel by the trimming tanks, and section 1 is submerged sufficiently to enable the submarine boat to be floated into the compartment therefor, where it is mounted or supported on suitable blocks, as indicated in Fig. 1. After this has been done the bow section 2 is submerged by means of its ballast and trim tanks to the proper depth and is then aligned with the forward end of the section 1, after which these two sections are secured tightly together in the manner described. To assist in properly aligning section 2 with section 1, the two sections of the hull may be provided with suitable graduation marks, whereby the depth of submergence of either section can be readily ascertained. After the submarine boat has been thus positioned in the testing compartment therefor, it may be tested in a known manner by subjecting it to the action of water under high pressure or the water in the compartment may be discharged therefrom and the boat subjected to air under high pressure, as well understood in the art. When the ship is not being used for testing submarine boats, the testing compartment is available as an additional ballast tank for submerging the ship to a greater depth than is possible by using only the ballast tanks exclusive of the testing compartment.

It is desirable, particularly during salvaging operations, that the boat be effectively moored in such manner as to be able to maintain its position under unfavorable weather and current conditions. With this object in view I provide, on the main deck 18 of section 1, a plurality of mooring devices such as capstans 42, upon which are wound mooring lines 43, these lines being passed or led through the customary chocks to the capstans. The capstans 42 are disposed in spaced relation along the opposite sides of the hull and provide means whereby the ship can be effectively moored and held in position. A capstan 44 is also preferably provided at the stern of the ship. The hull of the ship, including all openings and hatches therein, is water tight so that, in rough weather, the ship may be submerged to such an extent as to very materially reduce its buoyancy, materially reducing the abnormal stresses to which the mooring lines would be subjected, particularly during rough weather if the buoyancy of the ship were not thus reduced.

For lifting relatively light loads I provide

a suitable crane structure including a pole mast 45 mounted at the stern of the ship and a boom 46. This crane is of known construction and may be operated in a suitable manner for raising any object within the radius of the boom 46. The crane, as well as the capstans, and any other apparatus which it may be desired to position on the main deck 18, are preferably operated from suitable motors or engines positioned on the deck 15 so as to be effectively sheltered, operating shafts being passed through the main deck 18 by means of suitable stuffing boxes effecting a water tight closure about the same. This is well understood in the art and need not be illustrated nor described in detail. The crane structure is particularly valuable in making quick lifts of light loads as, when it is desired to lift one end of a disabled submarine boat for rescue purposes.

For lifting heavy loads I prefer to employ the form of apparatus disclosed in Figs. 7 and 8. In accordance with this apparatus I provide a plurality of rails 47 which are laid upon the main deck of the ship fore and aft thereof and suitably secured thereto. These rails form supports for transverse beams 48 mounted thereon and of a length to project beyond the sides of the hull. Each of the beams is provided with brackets 49 secured thereto, these brackets being adapted for securement to the outer rails 47 by being bolted thereto, as in Fig. 8, or in any other suitable manner. Each beam 48 may be provided with a central upwardly extending bracket 50 to which are secured stay rods 51 secured at their ends to the ends of the beam. The beam is adapted to receive, at its ends, suitable lines or hoisting cables 52 secured thereto in any suitable or preferred manner or, if desired, suitable blocks may be suspended from the ends of the beam, the cables being passed through pulleys in such blocks. The lifting lines or cables 52 are also suitably secured to the submerged object to be raised, such as a wrecked or disabled submarine boat. When using the ship to raise the object by the pontoon method, it is first submerged and, after the cables or lines 52 are suitably attached to the object to be lifted, the buoyancy of the ship is increased by emptying the ballast tanks thereof so that the buoyancy of the ship acts upon the object to exert a lifting effect thereon. In this manner, it is possible to exert a relatively great lifting effect and the stresses are distributed over the lifting structure or ship which is constructed to withstand such stresses. A further advantage of this method is that attachment may be made to the object to be lifted at a plurality of points and the lifting effect is exerted at such points, which is frequently of material advantage. Also, by properly regulating the buoyancy of the ship, the abnormal stresses induced on the lifting

or hoisting lines or cables by the motion of the waves are reduced to a minimum.

While I have illustrated the cross beams 48 as being equally spaced, this is not essential and, in fact, by releasing the brackets 49 from the rail 47, the beams 48 can be adjusted fore and aft of the ship into whatever position may be desirable for most efficient operation. This adjustment of the beams can be effected either manually or by suitable power means.

By the provision of the diving trunk 20 and the extensible section 21 thereof it is possible for the diver to enter the water well below the surface. By reducing the buoyancy of the ship to a minimum the depth below the surface at which the diver leaves the diving trunk is increased and the base from which the diver operates is maintained substantially steady since the ship, due to its reduced buoyancy, will not be materially affected by the roughness of the water at the surface. In this manner, the diver does not have to contend with the motion of the water at the surface which is a distinct advantage, particularly in rough weather.

As previously stated, the vessel is shown semi-diagrammatically for clearness in illustration and description. In fact, the vessel will be equipped with suitable propulsive machinery of any desired type, together with pumps, air compressors, compressed air reservoirs, hoisting machinery, de-compression chambers, winches, machine shop, steering gear, radio apparatus, submarine signaling apparatus, etc., and will constitute a self-contained sea worthy salvage and rescue vessel capable of maximum lifts through short distances when used as a pontoon, and also capable of heavy lifts to the surface from deep water in one operation.

What I claim is:—

1. In a ship construction, a sectional hull extensible and retractile, securing members carried by one of the sections of the hull, means for extending and retracting said members, and members on the other section cooperating with said securing members, the securing members when retracted holding the two sections firmly together.

2. In a combined testing dock and salvage ship, a main hull section having an air and water tight compartment opening through the forward end thereof and adapted for reception of a submarine boat to be tested, the forward portion of said compartment being of increased height, said hull section having a deck in the plane of the top of the aft portion of the compartment and a second deck in the plane of the top of the forward portion of the compartment, a bow hull section, and means for detachably securing said sections together and effecting a fluid tight closure of the forward end of the boat receiving compartment.

3. In a combined testing dock and salvage ship, a main hull section having an air and water tight compartment opening through the forward end thereof and adapted for reception of a submarine boat to be tested, the forward portion of said compartment being of increased height, said hull section having a deck in the plane of the top of the aft portion of the compartment and a second deck in the plane of the top of the forward portion of the compartment, said main hull section being further provided with a main deck above said second deck, a bow hull section having a main deck, means on the main decks of the two sections for initially aligning said sections and for holding them against relative transverse movement, and means for forcing said sections toward each other and releasably securing them together, said means also effecting a fluid tight closure of the forward end of the boat receiving compartment.

4. In a combined testing dock and salvage ship, a main hull section having a water tight bulkhead at its forward end, said section including a water and air tight compartment opening through the bulkhead and adapted for reception of a submarine boat to be tested, a bow section having its aft end closed by a water tight bulkhead, a member mounted on the bulkhead of the main section and enclosing the opening of said compartment, a second member on the bow section bulkhead and adapted for cooperation with the first member to form a fluid tight closure therewith, and means for forcing the two sections toward each other and detachably securing them together.

In witness whereof I hereunto subscribe my name this 2nd day of February, 1928.

LAWRENCE Y. SPEAR.
